PAGE 2

FIG. 4

FIG. 5

FIG. 1 is a front elevational view of a combined container and artificial fingernails, showing my new design in open condition;

FIG. 2 is a top plan view thereof wherein the lid is hinged at the rear and the raised interior platform is positioned with the artificial fingernails arranged in an arc thereon, the lower level of the platform and open end of the arc at the front of the box;

FIG. 3 is a side elevational view thereof;

FIG. 4 is a top perspective view of an embodiment of my new design wherein the lid is hinged at the sides; and

FIG. 5 is a top perspective view of another embodiment of my new design wherein the lid is hinged at the sides and the raised interior platform is positioned with the artificial fingernails arranged in an arc thereon, the lower level of the platform and open end of the arc at the rear of the box.

The top, bottom, and sides of the container are of flat planar configuration.

This is a division of design applications Ser. Nos. D. 9,451 and D. 9,453, both filed Nov. 17, 1967, and both now abandoned.

I claim:

The ornamental design for combined container and artificial fingernails, as shown and described.
